(57) **CLAIM**

The ornamental design for a grip for paper trimmer, as shown and described.

DESCRIPTION

FIG. 1 is a perspective view of the grip for paper trimmer;

FIG. 2 is a top view;

FIG. 3 is a front view;

FIG. 4 is a left end view;

FIG. 5 is a bottom view;

FIG. 6 is a rear view; and,

FIG. 7 is a right end view thereof.

The broken lines in the figures showing portions of the paper trimmer in FIGS. 1-7 are for illustrative purposes only and form no part of the claimed design.
